UNITED STATES PATENT OFFICE.

HOWARD B. CHANDLER AND JAMES A. FLEET, OF PORTLAND, MAINE.

ELECTRIC-LAMP SOCKET.

970,428.

Specification of Letters Patent. Patented Dec. 27, 1910.

Application filed August 28, 1908, Serial No. 450,635. Renewed September 8, 1910. Serial No. 581,094.

To all whom it may concern:

Be it known that we, HOWARD B. CHANDLER, a citizen of the United States of America, and JAMES A. FLEET, a subject of the King of Great Britain, and both residents of Portland, county of Cumberland, State of Maine, have invented certain new and useful Improvements in Electric-Lamp Sockets, of which the following is a specification.

10 Our invention relates to incandescent electric lamp sockets such as are now in common use, these sockets comprising a cylindrical shell containing the lamp connections with a screw threaded recess on the lower end into 15 which the lamp is screwed, and a hollow cap on the upper end fitting the cylindrical shell and detachably secured thereto and containing a hub with a screw threaded recess adapted to engage the end of the wall or 20 other fixture.

It has been found in practical use that the filaments of the new tungsten incandescent lamp are so frail and brittle that it is necessary to support them in a vertical position. 25 In the installation of the ordinary incandescent lamps many of the wall and chandelier fixtures are installed with the lamp sockets inclined at an angle usually about 45 degrees and in installing tungsten lamps 30 in such cases, it has been necessary to put in new fixtures or to insert a piece of bent pipe to bring the socket into a vertical position.

The object of our invention is to provide means for changing the ordinary straight 35 socket into an angle socket which may be applied to straight sockets set at an angle so that the lamp will be brought to a vertical position and to do this without changing in any way the parts of the original socket and 40 the invention consists of inserting between the two separate parts of the straight lamp socket an angle piece which will bring the lamp at any desired angle with the fixture.

We illustrate our invention by means of 45 the accompanying drawing in which is shown a common form of lamp socket provided with our attachment.

In the drawing, Figure 1 is a vertical section through the socket with our angle 50 piece inserted and Fig. 2 is a side elevation of the same.

B represents the socket proper consisting of an external cylindrical casing of thin metal inclosing the operating and connecting parts of the lamp with a hollow sheet metal cap A having a flange a' on its lower

end adapted to fit normally on the upper edge of the cylinder B. The cap A is also provided with a hub a² containing a screw threaded opening by which it is connected with the end of the fixture a. For the purpose of bringing the lamp to any desired angle with the fixture we insert between the two parts of the socket an angle piece C here shown as a hollow shell of thin metal having one end adapted to fit the flange a' of the cap and the other end provided with a flange c which is the duplicate of the flange a' and is adapted to fit on the upper end of the cylinder B. The angle piece C has a lining c' of fiber or other insulating material. The ends of the angle piece C are provided with the same coupling devices as are used on the ordinary lamp socket to secure the two parts together here shown as a small projection on the upper end of cylinder B adapted to fit a corresponding recess c² in the cap and a like recess c² in the lower flange c also adapted to receive the projection on the cylinder B.

It will be seen that by the use of our attachment the ordinary socket can be quickly converted into an angle socket or it may be used as a straight socket by removing the attachment. In connecting up it is only necessary to lengthen the wires d d a little and connect them to the socket proper in the usual way.

While we have referred to our invention as applying to a lamp socket, it may be 90 equally well used in a plug socket when it is necessary to bring the plug vertically from an angular fixture.

It is evident that the attachment may be made at any desired angle according to the 95 position of the straight socket and in practice these angle pieces will be made of a variety of different angles to suit different fixtures.

The angle socket as we make it, is compact and easily and quickly taken apart and put together, it may be cheaply made and the device constitutes a valuable and useful attachment for adapting an old device to a new use.

We claim;—

1. The herein described electric lamp socket of the class specified having an angle piece inserted between the two parts of the socket and adapted to be detachably secured to each part.

2. The herein described electric light

socket consisting of the socket proper, a hollow cap therefor adapted to be secured to the end of the fixture and a hollow angle piece adapted to be inserted between the socket proper and the cap and to be detachably secured to each part.

3. The herein described electric lamp socket including a cylindrical shell inclosing the lamp connections, a hollow cap adapted to engage the end of the fixture and to fit the end of said shell and to be detachably

secured thereto and a hollow elbow or angle piece the ends of which are adapted to fit the cap and the cylindrical shell respectively and to be detachably secured thereto.

In witness whereof, we have hereunto set our hands this 17th day of August, 1908.

HOWARD B. CHANDLER.
JAMES A. FLEET.
